UNITED STATES PATENT OFFICE.

HARRY LUCAS, OLIVER LUCAS, AND HAROLD WILLIAM FRANK IRELAND, OF BIRMINGHAM, ENGLAND.

AUTOMATIC ELECTRIC SWITCH.

1,420,935.

Specification of Letters Patent. Patented June 27, 1922.

Application filed May 26, 1921. Serial No. 472,836.

To all whom it may concern:

Be it known that we, HARRY LUCAS, OLIVER LUCAS, and HAROLD WILLIAM FRANK IRELAND, residing at Great King Street, in 5 the city of Birmingham, England, subjects of the King of Great Britain and Ireland, have invented certain new and useful Improvements Relating to Automatic Electric Switches, of which the following is a specification.

This invention relates more particularly to the electrical installations of motor vehicles, and has for its object to provide an improved automatic switch which connects 15 the dynamo and battery when a predetermined voltage is attained in the dynamo and disconnects them when the voltage falls below that value. One of the difficulties commonly experienced with apparatus of this 20 kind is that in the event of even momentary sticking of the contacts a heavy reverse current may flow from the battery into the dynamo, and as a reverse current is usually just as effective as a current of normal direction for holding the cut-out in action, the occurrence of a heavy reverse current may have serious consequences both to the 25 dynamo and the battery. This defect is by our invention avoided in a very simple and 30 effective manner.

Referring to the accompanying drawings:

Figure 1 is a diagrammatic sectional view illustrating an automatic switch constructed 35 in accordance with this invention.

Figure 2 is a plan of the switch.

In carrying the invention into effect as shown a flat iron base *n* carries at right angles to one side three iron members *o*, *p*, *q* 40 situated parallel with each other. Preferably the base is made from an iron strip with one end bent up at right angles to form one (*o*) of the aforesaid members, the other two being in the form of cylindrical iron 45 cores screwed or otherwise attached to the base. The middle core *p* is provided with a series winding *f*, and the other core *q* with a shunt winding *e*. On the upper end of the middle member is hinged (e. g., by a 50 knife edge *r*) an armature in the form of an iron bar *s*, which can rock on to either of the end members *o* or *q* and is normally held in contact with the unwound member *o* by a spring *t*. Brass stops *u* are provided 55 on the parts *o* and *q* to act as abutments for

the part *s*. Also the part *s* carries a spring blade *v* fitted with a contact *j* which can co-operate with a fixed insulated contact *k* carried on the base. To simplify wiring connections, one end of each of the windings 60 is electrically connected to the part on which it is mounted.

When the dynamo *m* is not in service the switch is open and the armature *s* is held by the spring *t* with one end resting on the 65 unwound member *o* and the contacts *j*, *k* are open. When the dynamo is in action the attainment of sufficient voltage enables the magnetization due to the shunt winding *e* to pull the armature over on to the end member *q* carrying the shunt winding and thus 70 close the contacts *j*, *k*. Current can now flow through the series winding *f* to the battery *l*. The direction of the flux produced by this winding is the same as that due to 75 the shunt winding, and the pull on the armature is augmented. The circuit for the magnetism is constituted mainly by the two wound cores *p*, *q* and the intervening portions of the armature and base. When the 80 dynamo stops, or its speed falls below that necessary to maintain a voltage equal to that of the battery the switch opens under the action of the spring *t*. But if the contacts stick current flows from the battery through 85 the series winding in the reverse direction. The flux due to this winding is now diverted (on account of the opposing magneto motive force of the shunt winding) to the unwound member *o* and the portions of the 90 base and armature between that member and the core *p* of the series winding. When the reverse current reaches a sufficient value the magnetic pull on the armature (assisted by the spring) which is opposed to that due to 95 the shunt winding causes the armature to rock back to its initial position and open the contacts; reverse current is therefore accompanied by a definite opening action on the armature, other than that due to the 100 spring, which pull increases with the magnitude of the reverse current.

Switches as above described are very simple and robust, are capable of being manufactured at small cost and possess all the required reliability in action.

Having thus described our invention what we claim as new and desire to secure by Letters Patent is:—

1. In automatic electric switches, the com- 110

bination comprising an iron base, three iron members arranged extending from one side of the base, an armature pivoted on the intermediate member, a series winding on the 5 intermediate member and a shunt winding on one of the end members, fixed and movable contacts carried on the base and armature respectively at the end adjacent to the said shunt winding, and a spring acting in 10 the direction for holding the contacts apart, substantially as described.

2. In automatic electric switches, the combination comprising an iron base, three iron members extending from one side of the 15 base, an armature pivoted on the intermediate member, a series winding on the intermediate member, a shunt winding on one of the end members, a fixed contact on the base, a spring blade on the armature, a contact 20 on the said blade for coacting with the fixed contact, and a spring acting on the armature in the direction for holding the contacts apart, the said contacts being arranged at the end of the switch adjacent to the shunt 25 winding, substantially as described.

3. In automatic electric switches, the combination comprising an iron base, an end member produced by bending up one end of the base, a pair of core pieces on the base parallel with each other and the said end 30 member, an armature pivoted on the core adjacent to the said end member, and capable of rocking in either direction relatively to the core, a series winding on said core, a shunt winding on the other core, one end 35 of each winding being electrically connected to its core, a fixed insulated contact on the base, a blade on the armature, a contact carried by said blade for coacting with the fixed contact, and a spring acting on the armature in the direction for separating the contacts, the said contacts being arranged at the end of the switch adjacent to the shunt winding, substantially as described.

In testimony whereof we have signed our 45 names to this specification.

HARRY LUCAS.

OLIVER LUCAS.

HAROLD WILLIAM FRANK IRELAND.
